UNITED STATES PATENT OFFICE.

HERMAN FREDERICK EBERTS, OF DETROIT, MICHIGAN, ASSIGNOR TO
JACQUES ROCHELEAU, OF WINDSOR, ONTARIO, CANADA.

PUSH-BUTTON FOR DOOR-BELLS.

SPECIFICATION forming part of Letters Patent No. 425,870, dated April 15, 1890.

Application filed December 6, 1889. Serial No. 332,861. (No model.)

To all whom it may concern:

Be it known that I, HERMAN FREDERICK EBERTS, of Detroit, in the county of Wayne and State of Michigan, have invented new and useful Improvements in Push-Buttons for Operating Door-Bells; and I hereby declare that the following is a full, clear, and exact description thereof, reference being had to the accompanying drawings, which form a part of this specification.

The nature of my invention relates to an improvement in door-bells, and has for its object to so construct a push-button case similar to those used as circuit-closers for electric systems as to give the necessary motion to wires for ringing ordinary jingle-bells or bells operated by a spring-actuated train of gears.

To this end my invention consists in the novel and peculiar construction of the several parts, as more fully hereinafter set forth and then definitely claimed.

As is well known, the ordinary electric push-button has a very limited longitudinal movement not exceeding one-quarter of an inch, which is entirely insufficient to actuate a distant bell through the old and well-tried system of wires and bell-cranks. At least one inch of initial movement of the wire is necessary to ring such bells or to set in motion a striking mechanism directly actuated by spring-driven clock-work.

Figure 1 is a vertical section of my push-button case. Fig. 2 is a side elevation of the bell-crank lever on the inner side of the door-frame without the slotted plate in which it is pivoted. Fig. 3 is an elevation of the said lever and its slotted plate.

In the drawings which accompany this specification, A is the base-plate of the push-button case, having a pair of lugs *a*, in which is pivoted a pendent lever *C*, passing through a slot *b* in the spindle *B*. The outward movement of the spindle *B* in the case or shell *A'* is arrested by the stop-pin *c*.

D is a rod pivoted at *d* to the pendent end 45 of the lever *C*. The length of the arm *C* below the pivot is twice that of its short arm above it, and consequently if the longitudinal throw of the push-spindle be one-quarter inch the inward movement of the rod *D* will be 50 double that.

The rod *D* passes through a small hole bored in the door-frame, where it is pivoted to a lever *E* by a transverse pin *e*. The said lever *E* is pivoted at its foot to a slotted plate 55 *F* by a pin *f*. In the eye *g* at the upper end of the lever *E* the bell-actuating wire is connected. The distance between the points *e* and *g* may be double or treble the distance between the points *e* and *f*, and therefore the 60 pull on the bell-wire will be in proportion—say one or one and a half inch—which will suffice to actuate the bell-wires of either of said systems.

What I claim as my invention, and desire 65 to secure by Letters Patent, is—

1. The combination of the base *A*, the shell *A'*, the slotted spindle or button *B*, passing through apertures in the shell and base, the lever *C*, pivoted to a support between the shell 70 and base and passing through the spindle *B*, and a rod *D*, attached to the free end of the lever, substantially as described.

2. The combination of the base *A*, the shell *A'*, the slotted spindle or button *B*, passing 75 through apertures in the shell and base, the lever *C*, pivoted to a support between the shell and base and passing through the spindle *B*, a rod attached to the free end of the lever, and a slotted plate *F*, carrying a lever *E*, hung in 80 the slot in said plate *F* and connected to the rod *D*, all substantially as shown and described.

HERMAN FREDERICK EBERTS.
